(57) **CLAIM**

The ornamental design for an adjusting device, as shown and described.

DESCRIPTION

FIG. 1 is a front view of an adjusting device showing my new design;

FIG. 2 is a front view thereof;

FIG. 3 is a right side view;

FIG. 4 is a left side thereof;

FIG. 5 is a top view thereof;

FIG. 6 is a bottom view thereof;

FIG. 7 is a perspective view thereof;

FIG. 8 is another perspective view thereof;

FIG. 9 is a front enlarged view thereof;

FIG. 10 is an enlarged rear view thereof;

FIG. 11 is an enlarged top view thereof;

FIG. 12 is an enlarged bottom view thereof;

FIG. 13 is an enlarged right side view thereof;

FIG. 14 is an enlarged left side view thereof;

FIG. 15 is an enlarged perspective view thereof; and,

FIG. 16 is another enlarged perspective view thereof.

The spindle is not shown in FIGS. 9 through 16 for convenience of illustration.
